UNITED STATES PATENT OFFICE

2,488,234

SPRAY FLUID ROTATED LAWN SPRINKLER

Charles H. Perry, Coral Gables, Fla.; Murrell E. Perry administrator of said Charles H. Perry, deceased

Application May 5, 1947, Serial No. 745,991

2 Claims. (Cl. 299—126)

1

This invention relates to sprinklers and particularly to the type of sprinklers set forth in my U. S. Patent No. 1,821,723, granted September 1, 1931. As shown in said patent, the sprinkler comprises generally an attaching base member provided with a nozzle, an open frame carried by said base member and having a pair of outwardly bowed arms connected at their upper ends by a sleeve or boss, a bearing-screw threaded through said boss in axial alignment with said nozzle, and a rotary spraying member mounted within said frame between the end of said nozzle and the inner end of the bearing screw, so that a jet of water issuing from the nozzle will impart rotation to said spraying member, the latter being formed with a wing having upwardly and outwardly radiating corrugations which spread the jet into small streams that separate into drops as they are projected over the area to be sprinkled.

In sprinklers of the type mentioned, wherein the rotary spraying member is arranged within an open frame, the side frame members obstruct and thereby interfere with an even distribution of the spray, so that V-shaped sectors radiating from said side members remain unwatered or only partly watered. Also, in localities where the rays of the sun are very hot, unevenness of expansion of the device permits the rotary distributor to become loose in its bearings after they have become only slightly worn, thereby making the sprinkler noisy in operation, or the rotary distributor may even become dislodged from its bearings.

An object of the present invention is to provide, in a sprinkler of the type referred to, means whereby the water will be distributed uniformly and completely over the area to be covered, without appreciable obstruction by the frame or any other part of the sprinkler.

A further object of the invention is to provide improved means for water lubricating the lower bearing of the rotary member, and for keeping said bearing clear of grit and dirt.

A further object of the invention is to provide an improved sprinkler structure whereby expansion of the frame due to the sun's rays will not loosen or release the rotary distributing element.

Other objects of the invention will appear hereinafter.

The invention will be more readily understood by reference to the accompanying drawings forming a part of this specification in which:

Fig. 1 is a front elevation of a sprinkler embodying the invention,

2

Fig. 2 is a side elevation thereof.

Fig. 3 is a vertical section on the line 3—3 of Fig. 1,

Fig. 4 is a transverse section on the line 4—4 of Fig. 3, illustrated upon an enlarged scale, and looking in the direction of the arrows,

Fig. 5 is an enlarged detail elevation of a portion of one of the frame arms,

Fig. 6 is a detail view of the inner face of a portion thereof looking in the direction of the arrows 6 of Fig. 5,

Figs. 7 and 8 are sectional views taken on the lines 7—7 and 8—8 respectively of Fig. 6.

Referring to the drawings, 10 indicates the base member of the sprinkler, which comprises a cap portion 11 internally threaded as at 12 to receive the coupling member 13 of a hose 14 or other source of water supply, and having an upwardly extending tubular portion 15, preferably integral therewith. Extending laterally from the cap portion 11 is an internally threaded lug 16 into which a supporting rod 17 may be secured when the device is used as a lawn sprinkler.

Threaded upwardly through the tubular portion 15 is a nozzle member 18 having a kerfed head 19 at its lower end, and a reduced upper end 20 extending above the portion 15 and terminating in a truncated conical bearing 21 for the rotary spraying member, as will appear hereinafter.

Extending upwardly from the base, and preferably integral therewith, is an open frame comprising a pair of arms 22—22 which are bowed outwardly and upwardly from diametrically opposite sides of the tubular portion 15, and then curved inwardly as at 23, and then downwardly as at 24 to a boss 25 formed integrally therewith. The boss 25 is provided with a screw threaded bore 26 into which is threaded a screw member 27. The member 27 is in axial alignment with nozzle member portion 20 and terminates at its lower end in a conical bearing 28.

Rotatably mounted in the frame between the lower and upper bearings 21 and 28 on the nozzle member 20 and screw 27 respectively, is a spraying member 29. The spraying member comprises an annular base 30 having an axial bore 31, and an integral propeller wing 32, connected to the base by an intermediate stem portion 33 having a troughed passageway 34 curved spirally upwardly in the path of the jet issuing from the nozzle 20. The base is provided with a conical seat 35 to fit the bearing 21 on the nozzle; and a conical seat 36 to receive the conical bearing 28 on the screw 27. By means of the screw 27 a close adjustment

of the bearing may be made, after which the screw is secured by a lock nut 37.

The seat 35 is in the annular base 30 is provided with grooves 38 which furnish vents to prevent retarding the stream as it passes through the bore 31; and, extending the full height of the bearings, they permit sand, worn metal or other foreign matter to be flushed from the bearings with the water dribble.

The concave inner face of the wing 32 is formed with radiating corrugations 39, which divide the water into a plurality of small streams which diffuse into drops as they are ejected over the area to be watered.

As hereinbefore stated, the side members of the frame of sprinklers of this type as heretofore constructed normally interfere with an even distribution of the spray; and it is one of the main objects of this invention to overcome this undesirable feature. To this end, the portions 23 of the frame members, which are in the path of the water as it leaves the wing 32, are provided in their lateral faces with grooves 40, which radiate in substantially the lines of direction of the minute streams from the corrugations of the wing above mentioned. These grooves are V-shaped in cross section with the apices or bottoms thereof extending to the center of the arms 22 at their outer faces; and the grooves on the opposite sides of the arm are staggered, as illustrated in Fig. 6, so as not to materially weaken the arms, and to permit the water to reach the areas otherwise screened by said arms. As the grooves approach the inner edge of the frame members, they are deepened, as indicated at 41, so as to pass the medial line of the inner edges of the frame members and to form the knife edges 42, as illustrated in Fig. 6. By this construction, the streams of water from the wing will enter the groove 40 either directly, or after having been parted by the knife edges 42, and will pass out of the grooves, as indicated by the broken lines in Figs. 7 and 8, thereby making a perfect coverage of the area being watered.

It will be noted that the arms 22 are comparatively thin throughout the greater portion of their length, but are thickened as they approach the base 10 and the boss 25, as indicated at 43 and 44 respectively. As the device becomes heated from the sun, the expansion of the frame is substantially compensated for by the longitudinal expansion of the wing member, the nozzle member 20 and the screw 27; so that the bearings will retain a snug fit and the wing member will not become loosened and fall out.

It is to be understood that a larger or smaller number of the grooves or notches may be provided in the arms of the frame, and that they may be of different widths.

I claim:

1. In a sprinkler of the type comprising a base having a nozzle, a bearing opposite to the nozzle, and a rotary spraying element mounted rotatably between the nozzle and bearing for rotation by a stream of water from the nozzle and operative to throw the water outwardly from its axis of rotation, a frame composed of arms connecting the base and bearing and positioned outwardly from the path of rotation of the spraying element, each of said arms having a portion in the path of the water from said element provided with grooves in its opposite sides extending substantially radially of the axis of rotation of said element, the grooves in each side of each arm extending at least to the center of the transverse thickness thereof and being staggered longitudinally of the arm relatively to the grooves in the opposite side thereof.

2. In a sprinkler of the type comprising a base having a nozzle, a bearing opposite to the nozzle, and a rotary spraying element mounted rotatably between the nozzle and bearing for rotation by a stream of water from the nozzle and operative to throw the water outwardly from its axis of rotation, said spraying element being provided with corrugations extending outwardly from its axis of rotation, a frame composed of arms connecting the base and bearing and positioned outwardly from the path of rotation of the spraying element, each of said arms having a portion in the path of the water from said element provided with grooves in its opposite sides extending substantially radially of the axis of rotation of said element and in substantial alignment with the corrugations thereof, the grooves in each side of each arm extending at least to the center of the transverse thickness thereof and being staggered longitudinally of the arm relatively to the grooves in the opposite side thereof.

CHARLES H. PERRY.
